UNITED STATES PATENT OFFICE.

JOHN F. LASH, OF TORONTO, ONTARIO, CANADA, ASSIGNOR TO ZEBULUN AITON LASH, OF SAME PLACE.

LETTER-FILE.

SPECIFICATION forming part of Letters Patent No. 416,036, dated November 26, 1889.

Application filed May 9, 1889. Serial No. 310,207. (No model.)

To all whom it may concern:

Be it known that I, JOHN FANNON LASH, a subject of the Queen of Great Britain, residing at the city of Toronto, in the county of 5 York, Province of Ontario, Dominion of Canada, have invented certain new and useful Improvements in Letter-Files, of which the following is a specification.

This invention relates to that class of letter-files which consist of two arches, in which each arch is so constructed as to be opened or separated to admit of papers being strung on the file, and when the arches are again closed the papers cannot fall off, and any 15 number of papers can be slipped past the junctures of the wires, and any particular paper may be taken off the file without unstringing the others.

I shall confine my description to a file of my own invention of the above class, although 20 my improvements consist materially not so much in the arrangement of the parts which make up the arches or the manner of opening and closing them as in the particular 25 method of maintaining the wires of the arches in contact after being closed, which may be more readily understood by reference to the drawing.

The figure represents a file constructed 30 with my improvements therein.

I will call the parts which go to make up an arch "a pair of filing-wires." Each arch consists of a filing-wire, as B, and an arched transfer-wire, as C.

35 A is the bed-plate.

B B' are the filing-wires, which may be either solid or tubular.

C C' are the arched transfer-wires, which may be either solid or tubular.

40 It may be observed that the filing-wires B B' are secured to the bed-plate in a rigid manner, and the arched transfer-wires C C' are made of one piece of wire, or at least should be joined rigidly together, so that 45 they will move in unison, and they are hinged to the bed-plate, so that their ends D D' will oscillate toward and come in contact with the points E E' of the filing-wires B B' when the file is being closed. It should be also observed 50 that the arched transfer-wires C C' are bent inward toward the bases of the filing-

wires B B' and hinged to the bed-plate much nearer to the filing-wires than would be the case if they were not bent inwardly, as shown. This is an advantage, for by this construction 55 the arched transfer-wires by their own weight and assisted by the weight of papers that may be transferred to them will fall backward and keep the file open when desirable, as in filing papers.

The particular method of interlocking the wires which compose the file, so as to maintain them in contact, is an important feature in this invention, and I will now describe it.

I construct one of the ends D of the arched transfer-wire C so that when it strikes its corresponding point E of the wire B it will engage it, so as not to slip past it when pressed with sufficient force to close the file, and I construct the other end D' of the other arched transfer-wire C' so that when it is slipped 65 past its corresponding point E' of the wire B' it will hook over it and engage it, so as not to slip back of its own accord and thus interlock the four ends of the wires, the natural tension or spring of the wires being sufficient to maintain a close connection. A simple and convenient method of forming a connection that can be easily hooked and unhooked consists in forming sharp points on the filing-wires B B' (adapted to puncture papers being strung thereon) and drilling out or hollowing the ends of the arched transfer-wires at D D' (if not already tubular) and filing them slantingly through to the cavities, so 70 that the sharpened points E E' of the wires B B' will fit into the cavities at D D' and press against the inner sides thereof. If the end D of the arched transfer-wire C is filed slantingly through to the cavity on the convex side of the arch, it will of course engage 75 with and retain the point E of the wire B when moved against it, as in closing the file, and if the end D' of the arched transfer-wire C' is filed slantingly through to the cavity on the concave side of the arch when it is slipped past the point E' of the wire B' it may be engaged therewith, and will consequently interlock each arched transfer-wire with its respective filing-wire, one arched transfer-wire 80 shoving and the other pulling its corresponding filing-wire. It may be observed that the

same result will be obtained if the construction above described be reversed by shaping the ends B B' as described for C C'.

Having now described my improvements 5 in the construction of duplex arched letter-files, I claim—

1. The combination of the filing-wires B B' and the arched transfer-wires C C', having their points respectively constructed and arranged 10 so that the wires in one pair will engage each other when pressed in contact by the closing of the file, and the wires in the other pair will engage each other when one is slipped past the other and adjusted against it so as to interlock the four wires by their natural spring, substantially as described.
2. The combination of filing-wires—such as C C' and B B'—C C' being rigidly connected together and working in unison when 15 moved, having their ends shaped, respect-

ively, as at D and E—viz., one wire shaped to engage the other in such a manner as not to slip past it when pressed in contact upon the file being closed—and also respectively as at D' and E'—viz., one wire being shaped so that 25 when slipped past the other it will engage it in such a manner as to retain it in contact by the natural spring of the wires—substantially as described.

3. In a letter-file, the combination of the 30 filing-wires B B' and the arched transfer-wires C C', bent inward, as at F, toward the filing-wires B B' and hinged to the bed-plate much nearer to the filing-wires than would be the case if they were not bent inwardly, as shown 35 in the drawings, substantially as described.

JOHN F. LASH.
